UNITED STATES PATENT OFFICE.

WILLIAM HENRY SCHAEFER, OF NEW YORK, N. Y.

MEANS FOR CHECKING ACCOUNTS.

1,255,796.

Specification of Letters Patent.

Patented Feb. 5, 1918.

Application filed August 13, 1914. Serial No. 856,636.

To all whom it may concern:

Be it known that I, WILLIAM H. SCHAEFER, a citizen of the United States, residing at New York, in the county of New York and State of New York, have invented certain new and useful Improvements in Means for Checking Accounts; and I do hereby declare the following to be a full, clear, and exact description of the invention, such as will enable others skilled in the art to which it appertains to make and use the same.

The invention relates to improvements in means for checking accounts.

The object of the present invention is to improve the means employed in restaurants, hotels, cafés, cabarets and similar places for checking accounts and to provide a simple, practical and efficient account checking means adapted to give all the transactions of the day in itemized form and capable of eliminating mistakes and of insuring cash for all orders taken and adapted also to enable the condition of the business to be ascertained at any moment by consulting a checker's list.

In many of the best hotels, restaurants, cafés, and eating houses, the waiter is required to make a payment to the cashier for every order which he serves, in advance, the waiter then collecting the amount due from the guest, as he is ready to depart. This system is complicated to some extent owing to the fact that a guest may even at the last minute order some two or three dishes which must be placed upon the check and thus it requires the waiter to make several payments to the cashier.

This system requires the services of a checker, a cashier, and the waiter, and with the necessary blanks or checks, and each person is required to keep check upon the other, and as a result of this, there is not liable to be a mistake made and the system is a protection to the guest as well as to the house.

The foregoing and other objects may be attained by means of the devices shown in the accompanying drawing and the system to be carried out thereby.

50 In the drawings:

Figure 1 is a plan view of the checker's list,

Fig. 2 is a similar view of the cashier's check,

55 Fig. 3 is a view of the guest check, and Fig. 4 is a face view of a dinner check.

Referring to the drawing, the numeral 1 designates the checker's list, designed to show the transactions of a day or any other period of time. This list is provided with a vertical column 2 headed "Waiter No." and in the column is given the number of the waiter. In the next column is given the name of the waiter, as shown at 3. The next column is headed "Checks opening No." "Guest—cashier", and under this heading is given the number of the guest checks, as shown at 4, and the cashier's checks, as at 5. The next column is "Checks closing No.", guest checks column 6 and cashier's 70 checks column 7. The guest checks or the checks containing the orders served and the cashier's checks are consecutively numbered as shown at 19 in Fig. 3 so that by having the numbers of the first checks used and the 75 numbers of the last checks used all the checks for a period of time may be ascertained. In practice the guest checks will be arranged in the form of a book and those for the cashier are preferably in the form of 80 pads but they may be arranged in any other desired manner as will be readily understood. The next column is the waiter's number and amount of each order as shown at 8. Also on the cashier's list are headings giving 85 the number of dinners served, as shown at 9, and the waiter serving the dinners given in the column 10.

In Fig. 2 is shown the cashier's check 1^a which gives the number of the waiter, and 90 the number of the cashier check, and in vertical columns 15 is arranged amounts running from five cents to nine dollars. The waiter's number on this check is placed at 11 and the cashier's number at 12 and in practice the amounts as shown ranging from five cents to nine dollars will be found ample to cover any individual order that may be served. This cashier's check is also provided with a stub 13 for the waiter and the 100 number of the cashier's check.

The cashier's check is separated from the stub at the dotted line 14 and the stub 13 remains on the pad with the checker for the latter's use and it enables him to ascertain 105 the cashier's checks which have been used during the preceding day or any other period. The amount of the order is preferably indicated by a suitable mark such as parallel lines drawn across the number indicating the amount on the cashier's check. The cashier's check is then taken by the

waiter to the cashier who receives from the waiter the amount of the order together with the said cashier's check which is used only when the cash system is employed, that 5 is, when the waiter pays the cashier for each order as he receives the same, without waiting for the guest to pay the bill. When the credit system is employed, that is, when the waiter does not pay the cashier until he receives 10 the amount of the bill from the guest, the cashier's check may be omitted and the waiter's check is then delivered to the cashier.

Fig. 3 shows a guest check 1^b and on this 15 check is given his number, the check number, and lines 16 are used for various articles served, and the amount to be collected are placed in columns 17 and 18.

In the operation of the account checking 20 means, the waiter upon taking an order on a check presents it to the checker who on his list marks the number of the waiter and the amount of the order. The checker also makes out the cashier's check in the 25 manner before described. When the guest pays the bill the waiter having previously settled for the same to the cashier returns the guest check to the checker. The checker then has his list and the guest check while 30 the cashier has the cashier checks and the amount on these must correspond and one is a check for the other.

When a dinner is served, the card shown 35 in Fig. 4 is used, and the time of giving the service of the meal and the amount or price of the dinner paid to the cashier by the waiter as indicated on the card which is returned to the cashier for use as a cashier's check after the meal is served, the number of 40 dinners served being shown on the cashier's list at the columns 9 and 10 which show the number of dinners and the waiter's number. The lines on the dinner card are for the various courses of the meal which in 45 practice are checked off by the checker as the course comes from the kitchen so that it will be impossible to duplicate a course surreptitiously or to sell a course which has not been served as the card must be returned to 50 the cashier. When the cash check system is not employed and the credit system is used, that is, when the waiter does not pay for the order served until after he receives the amount from the guest, he collects the 55 amount of the bill and turns the same over with the guest check or dinner card to the cashier.

All the numbers to be stamped upon the cards or checks are preferably done by rubber stamps.

By means of this system, the business of a restaurant or hotel may be carried on smoothly and without errors, there being three persons to have checks which correspond.

Various changes may be made in the details of the invention without departing from the spirit and scope of the invention as defined in the claims.

What is claimed is:—

1. Means for checking accounts including a plurality of consecutively numbered guest checks having an appropriately designated space for a waiter's number, lines for the articles served and columns for the price of the articles and the amount of the order, and a checker's list containing an appropriately designated column for the numbers of the waiters, appropriately designated columns for the opening and closing numbers of the guest checks, and an appropriately designated column for the amounts of the guest checks and the numbers of the waiters.

2. Means for checking accounts including a plurality of consecutively numbered guest checks having an appropriately designated space for a waiter's number, lines for the articles served and columns for the price of the articles and the amount of the order, a checker's list containing an appropriately designated column for the numbers of the waiters, an appropriately designated column for the names of the waiters, appropriately designated columns for the opening and closing numbers of the guest checks, appropriately designated columns for the numbers of the waiters and the amount of the guest checks, and appropriately designated columns for the number of dinners and the numbers of the waiters, and a dinner card containing the price of the dinner, the number of the waiter, and lines for the separate courses to enable the latter to be checked off as served.

3. Means for checking accounts including a plurality of consecutively numbered guest checks having an appropriately designated space for the number of the waiter and appropriately designated spaces for the articles served and the price of the same, a plurality of consecutively numbered cashier's checks, each containing an appropriately designated space for the number of the waiter and having printed on it amounts from five cents progressively upward to any suitable sum, and a checker's list containing appropriately designated columns for the numbers of the waiters and the names thereof, appropriately designated columns for the opening and closing numbers of the guest checks and the cashier's checks, and appropriately designated columns for the amounts of the orders and the numbers of the waiters.

4. Means for checking accounts including a plurality of consecutively numbered guest checks having an appropriately designated space for the number of the waiter and appropriately designated spaces for the articles served and the price of the same, a plu-

rality of consecutively numbered cashier's checks having printed thereon amounts from five cents progressively upward to any suitable sum, said cashier's checks having removable stubs with appropriately designated spaces for the number of the waiter and the number of the cashier's checks, and a checker's list including appropriately designated columns for the numbers of the waiters and the names of the same, appropriately designated columns for the opening and closing

numbers of the guest and cashier checks, and appropriately designated columns for the amounts of the orders and the numbers of the waiters.
